Patented Apr. 24, 1928.

UNITED STATES PATENT OFFICE.

EDWARD J. KOLODZIEJ, OF BUFFALO, NEW YORK.

SHOCK ABSORBER.

Application filed February 26, 1927. Serial No. 171,296.

This invention relates to that class of shock absorbers for vehicles in which liquid is employed as the resisting medium for absorbing the shock to which the vehicle is subjected.

In shock absorbers of this character as heretofore constructed it has been customary to supply each of a plurality of absorbers individually with resistant liquid both when originally installed and also when the same required replenishing due to waste and leakage. This is objectionable because of the inconvenience of attending to a plurality of shock absorbers from time to time and also because the absorbers are liable to operate with a pronounced difference in effect if the same are not uniformly supplied with liquid and thereby produce uncomfortable riding.

It is the object of this invention to provide means whereby all of the shock absorbers installed on a car are supplied constantly with a full charge of liquid so that they operate uniformly and also to effect such supply automatically and from a single source, so that less personal attention is required.

In the accompanying drawings:

Figure 1 is a perspective view showing the chassis of an automobile equipped with my invention.

Figure 2 is a vertical section of the pump for delivering the resistant liquid to a plurality of hydraulic shock absorbers in accordance with my improvements, the section being taken on line 2-2, Fig. 1.

Figure 3 is a similar view of the liquid supply reservoir forming part of my invention.

Figure 4 is a top plan view, partly in section of the liquid delivery pump, the section being taken in line 4-4 Fig. 2.

In the following description, similar characters of reference indicate like parts in the several figures of the drawings.

The chassis of the vehicle or automobile adapted to receive my invention may be of any suitable construction, that shown in the drawings consisting of a frame having longitudinal side bars 10, 10 and cross bars 11, 11, front and rear springs 12, 13, connected with the front and rear parts of the

side bars, and a front axle 14 connected with the front springs.

As usual the engine, as shown by dotted lines 15 in Fig. 1, is arranged within the front part of the frame.

Between each spring and the adjacent part of the frame is arranged a hydraulic shock absorber which may be of any suitable or approved construction and in the present case each of the absorbers consists generally of a cylinder 16 containing a movable piston adapted to press against a liquid resistant in the cylinder, such as oil, glycerine or the like, a rock shaft 17 journaled on the cylinder 16 and operatively connected with the piston therein for moving the latter, a rock arm 18 connected with the outer end of the rock shaft, and a link 19 connecting the rock arm with the adjacent part of the spring or some part moving therewith.

The means for supplying the several shock absorbers with resistant liquid are constructed as follows:

The numeral 20 represents a liquid reservoir or tank which is adapted to hold oil or the like for use as a resistant in the shock absorbers. This reservoir may be supported on any suitable part of the car, for example on the upper part of the engine, to which it is connected in the present instance by a bracket 21. This reservoir is provided in its top with a filler opening 22 through which the same may be replenished with resistant liquid after which this opening is closed by a plug 23. In its lower end, the reservoir is provided with an outlet 24 which contains a check valve 25 whereby liquid is permitted to flow out of the reservoir but not backwardly into the same.

Along a suitable part of the front axle or other part of the car which moves relatively to the frame is arranged the upright cylinder 26 of a liquid pump which in the present case is secured to one side of the front axle by a clamp 28 engaging the opposite side of the axle and connected with the pump cylinder by a bolt 29. At its upper end this cylinder is provided with an outlet 30 which is connected by a flexible main conduit 31 and rigid branch conduits 32 with the cylinders of the several shock absorbers and which contains a spring load-

ed check valve 27 whereby liquid is permitted to flow from the upper end of the pump cylinder to the shock absorbers but not in the reverse direction.

5 Within this pump cylinder is arranged a vertically reciprocating piston 34 which is provided with one or more check valves 35 whereby liquid is permitted to pass from the lower to the upper end of the cylinder but 10 not vice-versa. Secured with its lower end to this piston and extending through the upper end of the pump cylinder is a hollow piston rod, 36 which communicates at its lower end with the lower end of the pump 15 cylinder while its upper end connects by a flexible tube 37 with the outlet of the liquid reservoir.

By employing flexible connections between the pump cylinder and piston and 20 the absorber cylinders and reservoir, the axle and frame are free to move vertically relatively to each other without breaking any of the parts. The upward movement of the pump piston in the pump cylinder is produced by a spring 38 interposed between the 25 bottom of the pump cylinder and the underside of the pump piston. The downward movement of the pump piston is produced by a tappet 39 on one of the cross bars of the 30 frame which tappet is preferably provided on its underside with a rubber bumper 40 adapted to engage an enlarged head 41 on the upper end of the pump piston rod.

Whenever the tappet pushes downwardly 35 on the piston rod the liquid passes from the lower end of the pump cylinder through the pump piston to the upper end of this cylinder. Whenever the pump piston is raised by the spring in the pump cylinder liquid is 40 drawn from the reservoir into the lower end of the pump cylinder, while the liquid in the upper end of this cylinder is delivered to the cylinders of the several shock absorbers in accordance with their respective requirements.

Inasmuch as the discharge of the liquid from the pump cylinder is effected solely by spring pressure it follows that the pump piston will only be moved upwardly in the 50 same measure as the liquid enters the shock absorbers so that if the latter do not take up any additional resisting liquid then the pump piston will be held in a more or less depressed position.

55 During the vibration of the axle and frame relatively to each other while running the car, the tappet will only depress the piston an extent equal to that which it has been raised by the pump spring, and if for a period 60 no liquid is taken by the absorbers from the pump then the tappet will vibrate idly without influencing the pump, yet ready at all times to work the pump whenever replenishing of the absorbers is required.

65 Inasmuch as the pump is connected with

all of the absorbers the liquid is supplied uniformly and automatically to all of them in accordance with their needs without requiring any attention from the operator other than replenishing the liquid in the reservoir.

I claim as my invention:—

1. A plurality of hydraulic shock absorbers mounted on different parts of a vehicle, a liquid reservoir, and a pump which is actuated by relatively movable parts of the vehicle and whereby liquid is delivered from said reservoir to the several shock absorbers, said pump comprising a cylinder adapted to be mounted on one part of the vehicle, a piston arranged in the cylinder, a rod connected with said piston, a spring for moving the piston in one direction, and a tappet on another part of the vehicle and adapted to engage said rod and move the piston in the opposite direction.

2. A plurality of hydraulic shock absorbers mounted on different parts of a vehicle, a liquid reservoir, and a pump which is actuated by relatively movable parts of the vehicle and whereby liquid is delivered from said reservoir to the several shock absorbers, said pump comprising a cylinder mounted on one part of vehicle and provided at its upper end with an outlet communicating with said shock absorbers, a piston arranged in said cylinder and having valved ports whereby liquid is permitted to pass from the lower end to the upper end of said cylinder but prevented from flowing in the opposite direction, a tubular rod connected with said piston and opening into the lower end of said cylinder and extending with its upper end to the exterior of the cylinder and communicating with said reservoir, a check arranged in the connection between said reservoir and said cylinder, a tappet arranged on another part of the vehicle and adapted to engage said rod for depressing said piston, and a spring arranged between the bottom of said cylinder and the underside of said piston and operating to raise the latter.

3. A plurality of hydraulic shock absorbers mounted on different parts of a vehicle, a liquid reservoir, and a pump which is actuated by relatively movable parts of the vehicle and whereby liquid is delivered from said reservoir to the several shock absorbers, said pump comprising a cylinder mounted on one part of the vehicle and provided at its upper end with an outlet communicating with said shock absorber, a piston arranged in said cylinder and having valved ports whereby liquid is permitted to pass from the lower end to the upper end of said cylinder but prevented from flowing in the opposite direction, a tubular rod connected with said piston and opening into the lower end of said cylinder and extending with

its upper end to the exterior of the cylinder and communicating with said reservoir, a check arranged in the connection between said reservoir and said cylinder, a tappet arranged on another part of the vehicle and adapted to engage said rod for depressing said piston, and a spring arranged between the bottom of said cylinder and the underside of said piston and operating to raise the latter, said rod being provided at 10 its outer end with a head, and said tappet being provided with a rubber bumper for engaging said head.

In testimony whereof I hereby affix my signature.

EDWARD J. KOLODZIEJ.
